(57) **CLAIM**

The ornamental design for an armband with pouch, as shown and described.

DESCRIPTION

FIG. 1 is a top perspective view of an armband with pouch in accordance with my new design being worn by a child; FIG. 2 is a top perspective view of the FIG. 1 armband with pouch;

FIG. 3 is a front elevational view of the FIG. 1 armband with pouch;

FIG. 4 is a rear elevational view of the FIG. 1 armband with pouch;

FIG. 5 is a left elevational view of the FIG. 1 armband with pouch;

FIG. 6 is a right elevational view of the FIG. 1 armband with pouch;

FIG. 7 is a top elevational view of the FIG. 1 armband with pouch;

FIG. 8 is a bottom elevational view of the FIG. 1 armband with pouch; and,

FIG. 9 is a front perspective view of the FIG. 1 armband with pouch with the pouch open and ready to receive a mask. The broken lines in the drawings show environment only and form no part of the claimed design.

The broken line showing of a human figure and a mask is included for the purpose of illustrating environmental structure only and forms no part of the claimed design.
